UNITED STATES PATENT OFFICE.

WILLIAM B. FIELDS, OF ST. LOUIS, MISSOURI, ASSIGNOR TO FERGUSON-MCKINNEY MANUFACTURING COMPANY, OF ST. LOUIS, MISSOURI, A CORPORATION OF MISSOURI.

SHIRT SLEEVE.

Application filed July 28, 1923. Serial No. 654,443.

To all whom it may concern:

Be it known that I, WILLIAM B. FIELDS, a citizen of the United States, residing at St. Louis, Missouri, have invented a certain 5 new and useful Improvement in Shirt Sleeves, of which the following is a full, clear, and exact description, such as will enable others skilled in the art to which it appertains to make and use the same.

10 This invention relates to sleeves for men's shirts.

One object of my invention is to provide a sleeve for men's shirts that is particularly adapted for use in work shirts, owing 15 to the fact that it is equipped with a reinforcing element arranged on the underside of the sleeve and extending upwardly from the cuff towards the elbow portion of the sleeve.

20 Another object is to provide a sleeve for men's shirts that is provided with a placket which is of such construction that there is little liability of the inner end of the placket tearing.

25 Another object is to provide a shirt sleeve that is equipped with a double faced placket that is of neat appearance and inexpensive to construct.

30 And still another object is to provide a shirt sleeve in which a reinforcing element that is arranged on the underside of the sleeve forms part of the facing of the placket.

35 Figure 1 of the drawings is a plan view of a finished shirt sleeve embodying my invention, but with the cuff of the sleeve omitted.

40 Figure 2 is a plan view, showing the reinforcing element slit and arranged flat so as to illustrate how part of said element can be folded to produce superimposed portions that are used to form part of the placket facing.

45 Figure 3 is an enlarged plan view of the finished placket.

50 Figure 4 is a plan view, showing the two parts of the top facing of the placket secured to the placket slit in the sleeve material, the upper part of said top facing being folded back; and

55 Figure 5 is an enlarged transverse sectional view, taken on the line 5—5 of Figure 3, looking in the direction indicated by the arrows.

55 In Figure 1 of the drawings I have illus-

trated a finished shirt sleeve for men's shirts which is provided with a double faced placket and with a reinforcing element that is arranged on the underside of the sleeve at one side of the placket, so as to reinforce, 60 strengthen and impart greater wear-resisting properties to that portion of a shirt sleeve which is subjected to excessive wear, thereby producing a sleeve that is particularly adapted for use in men's work shirts. 65 The reinforcing element is composed of a piece of fabric A superimposed upon the piece of fabric B from which the sleeve is constructed, and in the preferred form of my invention, as herein illustrated, the piece 70 of fabric A that constitutes the reinforcing element is also used to form part of the placket facing. In constructing my improved sleeve I prefer to first form a vertical slit in the lower edge portion of the sleeve 75 material B, then superimpose the reinforcing element A on the sleeve material and secure the lower end portion of said reinforcing element to the sleeve material by a row of stitches 1 that extends along one side of 80 the placket slit in the sleeve material. The reinforcing element A has previously been provided with a vertical slit 2 that extends downwardly from the upper edge of said element parallel to one of the side edges of 85 said reinforcing element, so as to form what I will term a facing portion 3 which is adapted to be folded over the lower portion of the reinforcing element that is secured to the sleeve material at one edge of the 90 placket slit by the row of stitches 1. In Figure 2 I have shown the sleeve material 95 folded back and the facing portion 3 of the reinforcing element A arranged flat so as to clearly illustrate the construction of the placket and emphasize one feature of my sleeve which I believe to be broadly new, namely, forming part of the facing of the placket by a facing member which is adapted to be folded or doubled intermediate its ends, thus producing two facing portions, one of which is connected to the sleeve material at one edge of the placket slit in the sleeve material and the other connected to the sleeve material at the other edge of the 100 placket slit. The vertical slit 2 in the reinforcing element extends downwardly approximately one-half the length of said reinforcing element so that it can be doubled or folded over along the line 4 of Figure 4, 105

110

2
and said folded or doubled over portion 3 secured at one edge by a row of stitches 5 to the sleeve material B at the other side of the placket slit in said sleeve material. 5 The top facing piece 6 of the placket is also secured to the sleeve material and to the facing portion 3 of the reinforcing element A by the row of stitches 5, as shown in Figure 4. Thereafter the top facing piece 6 is 10 folded longitudinally along the row of stitches 5 and superimposed upon the facing portion 3, the rough edges of said parts being turned under and secured together by one or more rows of stitches 7 which are 15 continued around the marginal edge of the upper end portion of the top facing piece 6 so as to finish said facing piece and securely connect same to the sleeve material B. The upper end portion of the reinforcing element A can be finished and secured to the sleeve material B in any preferred manner, as, for example, by turning under the edge portions of said reinforcing element and securing said element to the 20 sleeve material B by one or more rows of stitches 8. If desired, the row or rows of stitches 8 that secure the reinforcing element to the sleeve material can be extended downwardly parallel to the seam formed by the 25 row of stitches 1 so as to securely attach the reinforcing element to the sleeve material at a point in proximity to and extending throughout the entire length of the placket.

30 A sleeve of the construction above described is admirably adapted for use in work shirts, owing to the fact that the portion at the underside of the sleeve extending upwardly from the cuff to the elbow portion of the sleeve is formed by two thicknesses of

material, and consequently, is capable of 40 successfully withstanding greater wear than the conventional work shirt sleeve whose corresponding portion comprises only a single thickness of material. The placket of the sleeve is provided with a double facing at 45 both sides of the placket slit, and as part of the placket facing is formed by one piece of material that is folded or doubled intermediate its ends, the inner end portion of the placket is not apt to tear and cannot 50 rip out, as is apt to occur with the conventional shirt sleeve placket in which the placket facing is composed of a plurality of short pieces of material that are connected together at the inner end of the placket by rows of stitches. In addition to being 55 strong and of neat appearance, a shirt sleeve of the construction above described is inexpensive to manufacture, as the co-operating parts of same are so constructed and arranged that they can be quickly connected together by a simple sewing operation.

60 Having thus described my invention, what I claim as new and desire to secure by Letters Patent is:

65 A shirt sleeve provided with a placket, a reinforcing element formed by a piece of material arranged on the underside of the sleeve at one side of the placket and extending upwardly from the cuff towards the 70 elbow portion of the sleeve, the piece that constitutes said reinforcing element being slit longitudinally and said slit portion being doubled over so as to form a portion of the placket facing, and a top facing for 75 the placket secured to said doubled over portion and to the sleeve material.

WILLIAM B. FIELDS.
